(57) **CLAIM**

We claim the ornamental design for a bolster pet cot, as shown and described.

DESCRIPTION

FIG. 1 is a top left perspective view of a bolster pet cot; FIG. 2 is a front view of the bolster pet cot of FIG. 1; FIG. 3 is a back view of the bolster pet cot of FIG. 1; FIG. 4 is a right side view of the bolster pet cot of FIG. 1; FIG. 5 is a left side view of the bolster pet cot of FIG. 1; FIG. 6 is a top view of the bolster pet cot of FIG. 1; and, FIG. 7 is a bottom view of the bolster pet cot of FIG. 1. The broken lines in the drawings illustrate portions of the bolster pet cot that form no part of the claimed design. The dotted lines shown in the figures illustrate stitching and form part of the claimed design.
